Primary Examiner — Susan E Krakower*Assistant Examiner* — Jerry Shiuan-Hua Hsu(74) *Attorney, Agent, or Firm* — CALDERON SAFRAN & WRIGHT P.C.(57) **CLAIM**

The ornamental design for a fixed mount steering helm, as shown and described.

DESCRIPTION

FIG. 1 is a front perspective view of a fixed mount steering helm according to my design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof; and,

FIG. 7 is a top plan view thereof.

The dash-dash broken lines illustrate portions of the fixed mount steering helm which form no part of the claimed design. The dash-dot broken lines depict boundaries of the scope of the claim, and form no part thereof.
